A. B. HURD, OF WATKINS, NEW YORK.

Letters Patent No. 67,118, dated July 23, 1867.

IMPROVEMENT IN CHURN-DASHER.

The Schedule referred to in these Letters Patent and making part of the same.

TO ALL WHOM IT MAY CONCERN:

Be it known that I, A. B. HURD, of Watkins, Schuyler county, State of New York, have invented certain new and useful improvements in Churn-Dashers; and I do hereby declare that the following is a full and exact description thereof, reference being had to the accompanying drawings, making part of this specification.

Figure 1 is a perspective view of my improved dasher.

Figure 2 is a similar view, showing a modification of the rod.

Figure 3, a central vertical section, showing another modification.

Like letters of reference indicate corresponding parts in all the figures.

My improvement belongs to that class known as atmospheric dashers. The invention consists in the employment of a plug at the bottom of the churn, over which the hollow rod slides to displace the air and force it into the cream. Also, in the employment of spiral-winged wheels inserted in the dasher-wings, and forming auxiliary agitators; and, further, in the employment of a thermometer attached to the bottom of the dasher-rod, and so arranged that it rests below the surface of the cream in churning, and may be drawn up through the eye of the churn-cover for inspection.

As represented in the drawings, A is the rod and B the dasher. The rod is tubular, for the passage of air, and may be made entirely of metal, as in fig. 1, in which case the valve *a* is situated in a cap that slips over the top, or it may be of wood, as in fig. 2, in which case the valve opens from the side of the rod, above the churn, or it may be of combined wood and metal, as in fig. 3, in which case the valve is situated inside at the junction of the wood with the metal. The lower end of the rod slides loosely over a plug, C, which may either be screwed into the centre of the churn-bottom, as in fig. 3, or simply rest free on the bottom by its own weight, as in fig. 1. By this arrangement, at the down stroke the plug enters the space in the tube below the valve, and displaces its bulk of the air, which is forced down around the sides of the plug, and into and through the cream, thereby imparting not only positive agitation, but exerting a beneficial influence upon the globules by the intermixture. It will be seen that the forcing of the air into the cream is positive and unavoidable; and in this respect it differs from all other atmospheric dashers with which I am acquainted, since in those the air is simply confined in a closed space, and is not really driven through the cream, if we except in pump-and-bellows churning. This arrangement is of the simplest and most effective character, since the parts producing the action are all in the bottom of the churn, out of the way, and not liable to disarrangement. The parts are easily washed, since it is only necessary, in separating, to lift the dasher off. The dasher is provided with four wings, *b b b b*, as usual. In these are cut holes *c e*, in which are fitted spirally-winged wheels *d d*, turning on bearings *f f*. Spiral wheels forming the entire dasher itself, irrespective of other parts, have before been employed. Mine differs from such, inasmuch as I insert the wheels in holes in the wings *b b*, to which they are auxiliary. The wheels arranged alone, simply pass up through and have a rotary motion imparted by the resistance of the cream, but cut through without thoroughly breaking it. In my dasher a positive up-and-down motion is given by the flat wings *b b*, while an auxiliary revolving motion is given by the spiral wheels, the combined action being to thoroughly break the globules. The flat wings, by lifting the cream, concentrate it over the openings holding the spiral wings. The agitation thus produced, combined with that from the air, is most thorough and effective. I attach a thermometer, D, to the lower end of the dasher-rod, as shown in fig. 1, sinking it flush with the surface; and where a metallic dasher-rod is used, casing it so as to protect it.

I am aware that thermometers have before been employed in churning, but so far as I am aware not at the bottom of the dasher. By locating it at that point I accomplish two important results where a dash-churn is employed: first, I keep it constantly beneath the surface of the cream in use, so that it will indicate accurately the temperature, and, second, I enable it to be drawn up through the eye of the cover of the churn, so that it can be inspected at any time without removing the cover. I am aware of no other device in which these combined advantages are secured. I do not claim broadly either spiral wings or the employment of a thermometer in churning.

What I claim as my invention, and desire to secure by Letters Patent, is—

1. The combination of the plug C, at the bottom of the churn, with the tubular rod A sliding over it for displacing the air, as herein set forth.
2. The combination of the spiral wheels *d* with the dasher-wings *b*, arranged and operating in the manner and for the purpose set forth.
3. The special construction and arrangement of the churn-dasher with all its parts, as herein specified.

In witness-whereof I have hereunto signed my name in the presence of two subscribing witnesses.

A. B. HURD.
